SELECTIVE STAGE ASSEMBLY

Edmund B. Kasold, Los Angeles, Calif.

Application April 25, 1941, Serial No. 390,284

3 Claims. (Cl. 272—22)

My invention relates to a selective stage assembly wherein a plurality of separate stage units are assembled and are selectively moved into a stage area or position wherein each stage unit is visible to an audience or other viewers of the action which occurs on the stage.

It is an object of the present invention to provide a stage assembly wherein a plurality of stage units are provided, each stage unit having thereon a set or an assembly of scenery parts comprising the scene of a drama, with means whereby these stage units may be consecutively moved through a closed path or circuit in such a manner that they may be individually brought into a position of use.

It is an object of the invention to provide a stage area, a plurality of stage units or sets which are separately movable, and means for guiding the movement of these stage units or sets so that they may be consecutively moved through a circuit and brought individually into the stage area.

A further object of the invention is to provide a stage assembly of the character set forth in the foregoing, including a number of vehicles which are separately movable along a track means defining a closed path or circuit, a portion of which path or circuit is disposed in the rear portion of the stage area, so that as the vehicles are moved through the path or circuit, they will be consecutively brought into the stage area. Accordingly, the scenes or sets assembled on these vehicles will be selectively brought into position for use in the stage carrier with a minimum of delay as compared to the time now spent in setting up scenes on a standard type of theatrical stage.

A further object of the invention is to provide a stage assembly wherein a plurality of separate stage units are movable through a circuit so as to be brought into cooperative relation to a stage area, and having means in association therewith whereby each stage unit may be moved forwardly in the stage area. A further object of the invention is to provide a track system on which stage units may be moved into cooperative relation to the rear part of a stage area, the portion of this track system adjacent the stage area being movable or shiftable so that its movement will result in movement of the supported stage unit in or into the stage area.

It is a further object of the invention to provide a stage arrangement of the character set forth herein wherein any one or more of the separate stage units may be selectively removed from or rearranged in the circuit. For example,

a stage unit may be made up so as to form a set or scene, and then may be moved into the circuit or path to replace a stage unit which has been removed from the circuit.

5 An important object of the invention is to provide an arrangement whereby the sets or stages in the taking of sound pictures or television may be quickly changed and brought into position before the camera or television scanning device.

10 Further objects and advantages of the invention will be brought out in the following part of the specification.

Referring to the drawings which are for illustrative purposes only:

15 Fig. 1 is a plan view, of schematic character, showing a preferred form of my invention.

Fig. 2 is an enlarged fragmentary elevational view taken as indicated by the line 2—2 of Fig. 1.

Fig. 3 is a fragmentary sectional view taken 20 as indicated by the line 3—3 of Fig. 1.

Fig. 4 is a fragmentary sectional view showing a roller and its supporting brackets.

Fig. 5 is a bottom plan view of one of the vehicles comprising a separate, movable, stage unit, shown in plan view in Fig. 1.

25 In Fig. 1 I show a plurality of stage elements or units E, individually identified as units E1 to E6 inclusive. These stage units E are shown in the form of separate vehicles of segmental form adapted for arrangement in the shape of a hexagon. Each unit E has a platform or floor portion 10 with a long front edge 11, a shorter rear edge 12 and radial end edges 13. To movably support each platform 10, I have shown wheels

30 or rollers 14, carried by brackets 15, as shown in Figs. 4 and 5, which are secured to radially disposed beams 16 and 17, which are in turn attached to the lower portion of the platform. The rollers 14, as shown in Fig. 5, are arranged on

35 concentric arcs 18 and 19, so that when the units E are disposed, as shown in Fig. 1, the wheels will engage inner and outer circular rails 20 and 21, of channel form, forming a part of a circular track system 22, forming a continuous path or

40 circuit through which the stage units E may be moved so that they will, one at a time, be brought consecutively into a position at the rear of the stage space A.

45 In Fig. 1 I have shown the stage unit E' in full lines, shifted forwardly from the position thereof indicated by dotted lines 23, so that the front edge 11 thereof will engage the rear edge 24 of a footlight stage section 25, which is customarily fixed in the position in which it is shown 50 in Fig. 1 and Fig. 3, in front of the area 26

occupied by the audience. So that this forward shifting of the stage unit E¹ may be accomplished, sections 29a and 21a of the rails 20 and 21 are mounted on a carriage 27 having a number of supporting means 28, carrying wheels 29, as shown in Figs. 2 and 3, which wheels 29 run in channel tracks 30, positioned as shown in Figs. 1 to 3 inclusive. When the carrier 27 is shifted rearwardly so as to bring the rail sections 20a and 21a into the position thereof indicated by dotted lines 20' and 21', these rail sections will be aligned with the circular rails 20 and 21, thereby completing the circular track system, and when the stage units E are moved through the circular path defined by the track system, the corners 31 thereof, will clear the rear edge 24 of the footlight stage section 25.

The stage units E are of such character that sets or scenery may be assembled thereon, and with a minimum expenditure of time, these stage units may be brought into the stage area A. The stage units E are separate, so that they may be removed from the circuit defined by the track system 22 as desired, and may be replaced by other stage units which have been made up prior to the placing thereof in the circuit. As a means for removing and replacing stage units E with relation to the circuit, I have shown the track system 22 as comprising a rear carrier 27a similar to the front carrier 27, this carrier 27a being movable on tracks 30a and carrying rail sections 34 and 35 of the rails 20 and 21.

Within the area outlined or surrounded by the track system 22, background scenery 37 may be disposed. For example, such background scenery 37 may represent mountains in the distance, visible to the rear of the stage. Such backgrounds 37 may be mounted upon a carriage 38 so that it may be moved forwardly on rails 39 which may be aligned, as shown in Fig. 1, with the members 30.

I claim as my invention:

1. In a stage arrangement of the character described, the combination of: means defining a stage space in which an action is presented; a plurality of separate stage units, each comprising

a separately movable vehicle having a platform to serve as a floor in said stage space and on which a set may be assembled; and track means forming a substantially closed path, a portion of which 5 path lies contiguous to the rear portion of said stage space, and through which said stage units may be moved in a circuit so as to be brought consecutively into a position at the rear of said stage space, a portion of said track means at the rear of said stage space being forwardly shiftable from its normal position relative to the remainder 10 of said track means, so as to move the stage unit thereon forwardly in said stage space.

2. In a stage arrangement of the character described, the combination of: means defining a stage space in which an action is presented; a circular track system disposed to the rear of said stage space, the portion of said track system contiguous to said stage space being forwardly shiftable; and a plurality of stage units each comprising a wheeled vehicle arranged to roll on said track system to a position on said forwardly shiftable portion of said track system, whereby each of said stage units may be consecutively brought into cooperative relation to said stage space and then, by the forward shifting of said portion of said track system, moved forwardly in said stage space to a position of use.

3. In a stage arrangement of the character described, the combination of: means defining a stage space in which an action is presented; a circular track system disposed to the rear of said stage space, the portion of said track system contiguous to said stage space being forwardly shiftable; a plurality of stage units each comprising a wheeled vehicle arranged to roll on said track system to a position on said forwardly shiftable portion of said track system, whereby each of said stage units may be consecutively brought into cooperative relation to said stage space and then, by the forward shifting of said portion of said track system, moved forwardly in said stage space to a position of use; and a background set behind said stage space in the area outlined 35 by said track system.

EDMUND B. KASOLD.
